(57) **CLAIM**

The ornamental design for a combined earphones and case, as shown and described.

DESCRIPTION

FIG. 1 is a front perspective view of the earphone of a combined earphones and case showing my new design, shown separately to show aspects of the design that are not visible when combined;

FIG. 2 is another perspective view thereof;

FIG. 3 is a front elevation view thereof;

FIG. 4 is a rear elevation view thereof;

FIG. 5 is a left side view of each earphone of the combined earphones and case;

FIG. 6 is a right side view of each earphone of the combined earphones and case;

FIG. 7 is a top plan view thereof;

FIG. 8 is a bottom plan view thereof;

FIG. 9 is a front perspective view of the case of the combined earphones and case, in open state shown separately to show aspects of the design that are not visible when combined;

FIG. 10 is a rear perspective view of FIG. 9;

FIG. 11 is a front elevation view of FIG. 9;

FIG. 12 is a rear elevation view of FIG. 9;

FIG. 13 is a left side elevation view of FIG. 9;

FIG. 14 is a right side elevation view of FIG. 9;

FIG. 15 is a top plan view of FIG. 9;

FIG. 16 is a bottom plan view of FIG. 9;

FIG. 17 is a front perspective view of the combined earphones and case, shown with all aspects of the design combined;

(Continued)

FIG. 18 is a front perspective view of the case of the combined earphones and case, in closed state shown separately to show aspects of the design that are not visible when combined; and,

FIG. 19 is a rear perspective view of the case of the combined earphones and case, in closed state shown separately to show aspects of the design that are not visible when combined.

The broken lines in the drawings depict the portions of the combined earphones and case which form no part of the claimed design.
